BREAD BOX OR SIMILAR ARTICLE

Nathan W. Roop, Columbus, Ohio

Application April 16, 1951, Serial No. 14,852

Term of patent 14 years

(Cl. D44—5)

To all whom it may concern:

Be it known that I, Nathan W. Roop, a citizen of the United States, residing at Columbus, in the county of Franklin and State of Ohio, have invented a new, original, and ornamental Design for a Bread Box or Similar Article, of which the following is a specification, reference being had to the accompanying drawing, forming a part thereof.

Fig. 1 is a perspective view of a bread box or similar article showing my new design with the lid shown in its closed position;

Fig. 2 is a similar view with the lid disclosed in its elevated or opened position;

Fig. 3 is a rear elevational view on a somewhat smaller scale; and

Fig. 4 is a bottom plan view thereof on the scale of Fig. 3.

I claim:

The ornamental design for a bread box or similar article, substantially as shown.

NATHAN W. ROOP.
